FIG. 2

FIG. 1

FIG. 4

FIG. 3

FIG. 1 is a side elevational view of a blower casing showing my new design.

FIG. 2 is a top plan view thereof as viewed from above relative to FIG. 1.

FIG. 3 is a bottom plan view of the blower casing as viewed from below relative to FIG. 1.

FIG. 4 is an end elevational view of the blower casing as viewed from the left relative to FIG. 1.

The end, shown in FIG. 4, illustrates the appearance of blower casing when looking at it from the left relative to FIG. 1 and the side opposite that shown in FIG. 1 is a mirror image thereof.

I claim:

The ornamental design for a blower casing, as shown and described.
